GARMENT HANGER

Carl B. Herzinger, Los Angeles, Calif.

Application October 19, 1937, Serial No. 169,816

2 Claims. (Cl. 223—95)

This invention relates to garment gripping devices that are adapted to be removably applied to coat hangers.

An important object of the invention is to provide a garment gripping device that may be readily applied to wooden or metal coat hangers of usual form, whereby women's skirts and men's trousers may be suspended therefrom.

A further object is to provide a garment gripping device that may be adjustably mounted on a coat hanger, whereby to adapt the same to garments of varying sizes.

I accomplish the above objects by means of the device described in the following specification reference being had to the accompanying drawing in which,

Fig. 1 is a side elevation of a coat hanger with my garment gripping devices mounted thereon and a woman's skirt suspended therefrom.

Fig. 2 is a side elevation of a coat hanger with my gripping devices mounted thereon and a pair of men's trousers suspended therefrom.

Fig. 3 is a perspective view of one form of the device for use in connection with the suspension of a woman's skirt.

Fig. 4 is a view similar to the above for use in connection with the suspension of men's trousers.

Fig. 5 is an enlarged cross section of the device for hanging a woman's skirt taken on line 5—5 of Fig. 1.

Fig. 6 is an enlarged cross section of the device for hanging a man's trousers taken on line 6—6 of Fig. 2.

Fig. 7 is a side elevation of a modified form of garment gripping device.

Fig. 8 is a cross section taken on line 8—8 of Fig. 7.

It is now the practice of garment cleaning establishments to deliver garments cleaned by them disposed on wooden or wire hangers, and as these hangers are of simple construction and inexpensive no charge is made for them. In some sections of the country notably the western section wooden hangers of arcuate form are used, while in the eastern section wire hangers of endless form are employed. While these hangers answer the purpose of the cleaner, they do not maintain skirts and trousers in an un-wrinkled condition, and furthermore garments suspended therefrom are often accidentally detached.

By means of my invention which is easily applied to the hangers of the type mentioned skirts and trousers suspended therefrom are not readily

detached, the resiliency of the gripping devices securely holding the garments in place and in proper form free from disarrangement.

In a preferred embodiment of my invention the garment gripping devices are constructed in two forms 5 and 6 intended for use with garment hangers H of wooden arcuate form and a modified form 7 intended for use in connection with wire hangers.

Form 5 is intended for suspending women's 10 skirts from hangers, while form 6 is designed to engage and suspend men's trousers. Both forms are constructed from a single piece of resilient wire, bent upon itself to form resilient garment gripping members 15 and 16, the uppermost end 15 being formed into an angular loop 8 consisting of a lateral cross piece 9 upwardly and outwardly extending portions 10 and 11, and longitudinally extending portions 12 and 13, a lateral bridge member 14 secured to the longitudinal 20 portions 12 and 13, maintaining the two portions in spaced relation and forming a closed loop. Bridge member 14 and the cross piece 9 form a lock when the devices are mounted on the hanger H and a garment suspended therefrom and prevent a movement of the devices when in an adjusted position, the tension of the garment or skirt suspended therefrom against the resilient legs 15 and 16 slightly canting the devices to 25 lock the same as heretofore set forth.

The outer portions of the devices extending from the bridges 14 are bent downwardly to form garment engaging legs 15 and 16, the ends of said legs being secured together by a garment engaging member 17 formed of a frictional material such as rubber, or a similar substance.

The gripping devices 6 for suspending men's trousers therefrom are exactly similar in all respects to the form just described, the only difference being that the ends of the legs 15 and 16 are not secured together, each end being provided with a garment engaging member 18 formed of the same material as members 17 used on form 5.

The modified form illustrated in Figs. 7 and 8 is intended for use in connection with the endless wire garment hangers 20 heretofore mentioned. In this form the only difference between the preceding forms resides in the manner of attachment of the bridge member 21, it being pivotally mounted on the longitudinal portion 13 of the device in order that the same may be readily mounted on the cross bar 22 of the endless hanger. In Fig. 8 the bridge 21 is shown 55

with its free end resting on the upper surface of horizontal bar 22 of the hanger 20.

The method of attaching the modified form of device on the horizontal bar 22 of the hanger 20 is quite simple, the pivoted bridge member being swung downwardly (as shown in dotted lines of Fig. 8) in order that the longitudinally extending portions 12 and 13 may be passed above the bar 22 of the hanger to permit the bridge member 14 to swing into operative position as shown in full lines, its under face resting on the cross bar 22 of the hanger.

The method of utilizing the gripping members in connection with the hangers heretofore described is comparatively simple. The forms used in Figs. 1 and 2 being merely slipped over the ends of the wooden hanger or support H and adjusted laterally thereon to conform to the size of the skirt that is to be suspended therefrom. When suspending a skirt S the legs 15 and 16 of the device are inserted in its upper open end, as shown in Fig. 2 and the devices are then drawn apart. The resiliency of the depending legs securely engaging the skirt and holding the same in positive engagement. In the form illustrated in Figs. 4 and 6 the legs 15 and 16 are inserted in the ends of the trousers' legs 25 and the devices are drawn apart to firmly engage the fabric of the trousers and securely hold them against dislodgement. The function of the devices shown in the modified form illustrated in Figs. 7 and 8 is exactly the same as the forms shown in the preceding figures of the drawing.

From the above it will be seen that I have devised an extremely simple device that may be readily attached to garment hangers of ordinary form and which will securely hold the garments

suspended therefrom against accidental dislodgement.

I claim:

1. A garment hanger comprising a support, and a pair of garment engaging members slidably mounted thereon, each of said garment engaging members being formed of a single piece of spring wire bent upon itself to form depending garment engaging legs, bridge means connected with the legs adjacent the bent portion to form a closed loop, the bridge means engaging the upper edge of the support and the bent portion engaging the lower edge of the support, whereby when a garment is supported from the legs of said garment supporting members the tension of the suspended garment against the legs of the hangers will cant the looped ends of the garment supporting members to lock the same in rigid engagement with the support. 5

2. A garment hanger comprising a support, 20 a pair of garment engaging members slidably mounted thereon, each of said garment engaging members being formed of a single piece of resilient wire bent upon itself to form depending garment engaging legs, a bridge member secured 25 to the legs of the garment engaging members adjacent the bent portion to form a closed loop, the bridge portion resting on the upper edge of the support and the bent portion engaging the lower edge of the support whereby when a garment is supported from the legs of said garment engaging members the tension of the suspended garment against the legs of the hangers will cant the looped ends of the garment supporting members to lock the same in rigid engagement 30 with the support. 35

CARL B. HERZINGER.
